UNITED STATES PATENT OFFICE

118,813

DESIGN FOR A COMBINED NAPKIN DISPENSER AND DISPLAY HOLDER

Victor Wayland Cornelius, Eastland, Tex.

Application November 14, 1938, Serial No. 81,083

Term of patent 14 years

To all whom it may concern:

Be it known that I, Victor Wayland Cornelius, a citizen of the United States, residing at Eastland, county of Eastland, State of Texas, have invented a new, original, and ornamental Design for a Combined Napkin Dispenser and Display Holder, of which the following is a specification, reference being had to the accompanying drawing forming a part thereof.

In the drawing:

The dominant feature of my design resides in the portion illustrated by solid lines.

I claim:

The ornamental design for a combined napkin dispenser and display holder, substantially as shown and described.

VICTOR WAYLAND CORNELIUS.
